DESIGN FOR A TOY GUITAR

George F. Kearney, New York, N. Y.

Application December 19, 1945, Serial No. 124,864

Term of patent 3½ years

(Cl. D34—15)

To all whom it may concern:

Be it known that I, George F. Kearney, a citizen of the United States, residing at Bronx Borough, in the city of New York, Bronx County, and State of New York, have invented a new, original, and ornamental Design for a Toy Guitar, of which the following is a specification, reference being had to the accompanying drawing, forming a part thereof, in which:

Fig. 1 is a front elevation, and Fig. 2 an edge elevation of the toy guitar showing my new design.

The back of the toy guitar is conventionally plain.

I claim:

The ornamental design for a toy guitar, as shown and described.

GEORGE F. KEARNEY.
